(57) **CLAIM**

The ornamental design for a multi passenger electric vehicle, as shown and described.

DESCRIPTION

FIG. 1 is a perspective view of a multi passenger electric vehicle showing our new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top elevational view thereof; and,

FIG. 7 is a bottom elevational view thereof.

The broken lines are included for the purpose of illustrating only and form no part of the claimed design.
